BUILDING CONSTRUCTION

Arthur M. McLellan, Los Angeles, Calif., assignor
to McLellan Steel Development Corporation, a
corporation of Nevada

Application April 5, 1937, Serial No. 135,118

3 Claims. (Cl. 72—118)

My invention relates to building walls and while it applies in general to many types of walls it is more particularly directed to plaster and cement hollow walls which are re-enforced by an intermediate steel structure or frame.

One object of the invention is to improve upon the steel structure set forth in my Patent No. 2,053,487 and to provide maximum rigidity combined with lowered cost.

Another and equally important object of the invention is to provide improved means for constructing and anchoring plaster walls in general; not only to provide for properly anchoring the inside and outside walls respectively to the aforesaid steel structure but also to improve the art of plastered walls in general.

Specifically, it is an object of this invention to provide a combined furring device, lath-anchor and lath-stretcher whereby the lather may properly stretch wire or metal lath; fasten the lath to a steel or wood structure; and automatically fur or space the same all in a simple set of operations and with a simple, low-cost device which takes the place of a furring nail and produces results impossible of attainment with present devices of this sort.

Another object of the invention is to provide a building wall comprising respectively: the strong low-cost steel frame of the general type set forth in the aforesaid patent, the inside plaster wall, the outside cement or stucco wall, and layers of water-proof felt on either side of the steel frame and between the frame and the corresponding plaster or cement wall; all so articulated as to provide a relatively homogeneous structure of high tensile strength and resistance while characterized by a certain adaptability to thermal stresses and sudden shock.

It will be understood that, in the case of light-weight and other fabricated steel structures, suitably rigid metal lath must be employed to comply with the usual requirements and the lath must either be of such character as to readily retain wet plaster, or it must be provided with an impervious backing. The latter is preferable since plaster-faced fabricated steel structures are not sufficiently moisture proof without paper, felt or the like.

To meet such demand there have appeared on the market a great variety of ribbed or otherwise re-enforced metal lath provided with impervious backing. These have certain of the advantage sought but have the objection of high price, high cost of application, and high shipping and pack-

ing rates because of their more or less rigid nature.

In this connection it is an object of this invention to provide a method whereby a lather of ordinary skill may employ common rolled felt or paper, common wire mesh, and a multiplicity of simple fasteners, and, with no more effort than is now used in applying complete fabricated lath, construct an ideal plaster base as a substantially integral part of the building or wall.

Another object of this invention is to provide a metal or wire lath and plaster wall which is so secured or suspended that the said wall is carried directly by the steel frame or other structural elements of the building and does not depend upon the tensile strength of furring nails, strips or the like.

In fact, considering all features of this invention collectively, it is an object of this invention to provide a wall of great strength, light weight and low cost by employing common steel bar stock, common building paper or felt in rolls, common wire mesh in rolls, manufactured plaster-and-lath anchors of the type disclosed by this invention, and a plurality of pre-manufactured links formed from common round stock; whereupon the applied skill of an electric welding expert, a lather and a plasterer will provide a complete wall or a complete building comprising walls, floors and roof respectively.

In carrying out my invention I provide, to replace the ordinary furring nail or like device, a simple metal device which in the case of frame buildings or the like may be secured by a common nail and which in the case of steel structures is readily tied to a structural member. In either event this device when attached provides for anchoring an underlying sheet of paper or felt which is put in place as the work of fastening the devices progresses. These devices, suitably spaced, not only anchor the paper or felt but also provide a furring projection which stands above the surface of the paper while being held securely against any structural part immediately underlying the paper.

It is a salient feature of the invention that the said simple device upon having been "cinched" to retain the paper and to lock itself to the structure, presents a relatively long length of wire projecting therefrom. Now common wire mesh may be placed over the paper; the said devices acting to fur or space this mesh with respect to the paper; the said wire lengths being then brought thru the openings in the mesh and preferably after passing under a strand of the mesh

remote from the device proper. Now the free end of each wire length is grasped as with pliers and pulled back in the direction of the furring portion, whereupon the mesh is forcibly stretched to any reasonable degree to take up all slack and to cause all parts of the wire mesh to evenly space themselves with respect to the paper.

Now the paper is held in place by the furring means; the furring means hold the wire mesh properly spaced; and the wire extensions of said means hold the mesh suitably and permanently stretched; while the mesh is so articulated with the structural elements of walls that any load subsequently imposed upon it is transmitted directly to the building frame and plaster subsequently applied to the so-formed lath becomes a part of the wall in the truest sense of the word.

In applying features of this invention to the building or wall set forth in the aforesaid patent, I propose to employ the same girders as are therein described. These girders I propose to tie together with the diagonal links or braces in much the same manner as therein described except that I have discovered an arrangement of parts, described hereinafter, whereby only one-half as many braces or diagonal ties between the girders, will give practically the same results at reduced cost. Instead of the horizontal ties or links parallel to the front and back faces respectively of the wall I propose to first tie the girders together with the diagonal braces only, to form the hollow wall, and then I propose to run long rods horizontally along the front and rear faces of the wall and to weld these rods to each girder adjacent each load-supporting shoulder.

These rods not only take the place of the aforesaid horizontal links at reduced cost of fabrication but they also provide what may be termed ribs for the co-extensive felt-and-metal lath which by reason of this invention I am now enabled to manufacture at the site, from building paper and common wire mesh with the aid of a pair of pliers and a multiplicity of the new devices.

I have illustrated by the accompanying drawings one complete practical embodiment of my invention in the form of a hollow, water-proof, steel re-enforced wall having a cement or concrete outer surface and a finished plaster inner surface.

In the drawings:

Figure 1 is a fragmentary face view or front elevation of the steel frame employed.

Figure 2 is a vertical section thereof and showing the inner and outer surfaces in place.

Figure 3 is a diagram for more fully explaining the unique arrangement of the structural parts shown in Figures 1 and 2.

Figure 4 is an enlarged detail side elevation of one of the said devices in the position representing one of the early steps in the application of same.

Figure 5 is a similar view showing the device in final position and acting to retain the underlying paper, and to fur the wire mesh, and to hold the wire mesh suitably stretched.

Figure 6 is a face view or front elevation of the paper-backed lath formed by this invention, and in place on the steel frame shown in Figures 1 and 2 respectively.

Figure 7 shows a modification of the paper-fastening means.

More specifically, the numeral 10 indicates the girder which is manufactured from the two parallel vertical rods 11, 11; the plurality of transverse horizontal links 12, 12; and the diagonal

links 14, 14. This girder is not unlike that described and claimed in the aforesaid patent. These girders are placed in the spaced relationship shown to form a self-sustaining frame when connected by the diagonal X-braces 15, 15, etc.; 5 not unlike the braces shown in the aforesaid patent.

In the present case however I propose to space these X-braces thruout the frame so that then there is an open space such as indicated at 16 10 between each pair of braces both horizontally and vertically. In other words, each two adjacent girders are held together by a vertical row of X-braces spaced from each other vertically, the braces of one vertical row being staggered 15 with respect to the braces of adjacent vertical rows. By this arrangement each of the four looped ends, 16a, 16b, 16c and 16d respectively of each brace joins the corresponding rod 11 of the corresponding girder at a point close to the 20 point at which the corresponding looped end of the X brace of a staggered adjacent row also joins the same rod 11.

Also, in conformity with the present invention I show the lower ends of each X-brace joining 25 with the same rods 11 as do the corresponding upper ends of the braces of an adjacent vertical row of X-braces.

Specifically, where the lower ends of an X-brace join front rods of adjacent girders, the 30 upper ends of the next lower brace, which is of course in the next vertical row, also join front rods. Likewise, where the upper ends of an X-brace join with rear rods of adjacent girders, the lower ends of the next uppermost X-brace, which 35 is in the next row, joins with rear rods.

Figure 3 is a diagram which brings out this point more clearly and in this diagram the members corresponding to those shown in Figures 1 and 2 respectively are similarly numbered. This 40 diagram also illustrates an obvious modification of the invention in which the parts are welded together without the use of load supporting shoulders to encompass the girder rods.

In fact the present Figures 1 and 2 respectively, show the hooked or looped ends of the braces and ties as not completely encompassing the rods of the girders. Inasmuch as these ends are each welded to the girder rods and to adjacent ends these semiannular shoulders are found to have the proper load-supporting characteristics, particularly inasmuch as the truncated ends 18 of each do not exactly overlie the corresponding terminations of adjacent loops or ends. It will also be understood that each X-brace originally consists of two crossed rods which have been welded as at 18 to form an X.

The arrangement of parts shown provides groups of four hooked ends as generally indicated by the numeral 20, and other groups of only 60 two hooked ends are generally indicated at 21. For example, traversing the length of any girder rod front or rear it is found that the groups of four ends alternate with groups of two ends. Also, the arrangement of parts described, and 65 considering an extensive wall made up by the arrangement of parts, shows an ideal arrangement of diagonal braces each weaving thru the structure to join with a front girder rod and then with the back rod of the next girder, and 70 then with the front rod of the next succeeding girder, and so on thruout diagonal paths across the entire frame.

When the girders are so assembled together with the X-braces, the structure is still incom- 75

plete until all girders are tied to each other both front and rear. In the present invention this is done with co-extensive rods 22 at the front and 23 at the rear. Rods 22 are shown as placed 5 immediately over the groups of two shoulders where they are disposed at the front of the frame, while rods 23 are placed where the groups of two shoulders appear at the rear. As a consequence these rods are alternated so that first one such 10 rod appears at the front of the frame while the next uppermost rod appears at the rear.

Thus, as compared with the structure set forth in the said patent, the present invention requires only one-half as many X-braces and only one-half as many horizontal tie rods; the present invention 15 also providing for using long lengths of common stock in place of a plurality of specially formed links. The two looped ends of the girder links form a supporting shoulder for the adjacent 20 part of the horizontal rods 22 and 23, respectively, and provide for these rods being welded to the girders by being welded to the girder rods as well as to the looped ends of the girder links.

In addition to the rods 22 and 23 finally completing an exceptionally strong light-weight and 25 low-cost frame, these rods have the added function of forming at no additional cost, the re-enforcing rods of a co-extensive metal and felt plaster base the equal of the best on the market, 30 not to mention the fact that this invention automatically provides for the lath or "plaster-base" becoming a welded part of the whole structure.

The device 4, may be variously constructed as 35 those skilled in the mechanical arts will realize, but is here shown as formed of wire first coiled as at 25 in several superimposed convolutions outwardly to form a sleeve generally indicated at 26. Then the wire as at 27 is introverted and passing back thru the coil or sleeve emerges from 40 the lower end thereof and is formed into a greatly elongated U-shaped loop generally indicated at 28. The loop terminates in an end 29 normally 45 outside of the sleeve 26 as indicated by broken lines in Figure 4, but by reason of the soft or ductile nature of the wire and the shape of the loop, said end is readily inserted in the sleeve 26 50 as shown in full lines of Figure 4.

Building paper or felt 30, 30 is now placed over 55 either face of the wall provided by the steel parts just described and rests upon the rods 22 or 23 as the case may be. Where the paper rests direct against rods 22 or 23 it is provided with perforations of any suitable shape altho it is here shown as provided with narrow elongated cuts or slots 60 31 normal to the plane of the rods and thru which the looped end of device 4 is readily inserted. It is an easy step to force the looped end 65 of the device 4 thru the slot and to then retract it again with the loop of the device hooked around the underlying rod, as shown in Figure 4. At the same time the extreme end 29 is passed thru the sleeve 26.

Now the end 26 is grasped, as by pliers indicated in broken lines at 32 in Figure 4, and the 65 end 29 is pulled to bend the wire sharply over the upper edge of the sleeve as at 34 and to dispose the wire parallel to the paper but in spaced relationship as at 35. This last operation 70 may be done either before or after laying the common wire mesh 36 over the paper. Preferably the paper is attached co-extensively all over the wall surfaces of a building in which position is securely held by the multiplicity of devices 4 which are suitably numerous and suitably closely spaced as those skilled in the art of applying 75

paper and lath will understand. However, the wire stretching feature of the device 4 permits of using fewer devices since the wire mesh may be held taut between two well spaced points.

When the wire mesh is put in position the extreme end 29 of the device 4 is fished from under the wire mesh, as with a pair of pliers, to come up behind a strand such as 36a, well removed from the sleeve portion of the device. Now the end of the wire 29 is pulled back toward the center of the device 4 and this act will serve to stretch the wire mesh as much as required. The soft wire of device 4 bends readily as at 38 over the corresponding strand 36a of the wire mesh and automatically locks there. The now remaining portion of this wire end 29 can now be bent over a second strand such as 36b remote from strand 36a so that it eventually becomes locked permanently when the now formed lath is imbedded in plaster.

When wire mesh and paper have thus been placed co-extensively over a building or wall the job is now ready for plaster; the wire mesh being now held well stretched and properly spaced over and above the felt or paper. The lath provided by this invention actually consists of paper backed with spaced parallel re-enforcing rods and topped with wire mesh strongly stretched from rod to rod and tied directly to the rods by wire devices which are now locked so that the wire would part before the locking means would release itself. The re-enforcing or backing rods of the lath are in turn a structural part of the steel frame and replace the transverse horizontal links previously used by me.

It will be apparent now that during and after 35 application of plaster the wire mesh will remain stretched and tight and when the plaster has set the corresponding surface walls are locked and tied to the structure in an efficient and novel manner to carry out the objects of this invention. 40 Those familiar with the relative co-efficients of expansion of various materials employed herein and with the stresses and strains to which these walls are subject will appreciate that this invention provides an ideal in building construction and 45 with suitably heavy wire mesh and the use of the proper cements or plastics, floors and roofs as well as side walls may all be constructed according to this invention to provide a double-walled monolithic structure or building in which 50 the spaced walls are tied together by and are integral with an intermediate steel frame capable of supporting all loads to which the building is subject and without the monolithic walls being required to carry any imposed loads, or act other 55 than a barrier to natural elements.

I have been specific in the foregoing as to construction and arrangement of the parts and devices employed but this is done only in the nature 60 of a complete practical disclosure and not to impose limitations to the scope of my invention which is of a broad nature. Therefore modifications of the embodiment illustrated are within the scope of this invention which is hereinafter 65 claimed.

For example: In Figure 7 I have shown a modified form of the device 4 for use in buildings where a nail 40 or the like can be driven into the wall 41 thereof. In this form the end 29 leaves the 70 sleeve directly at the top thereof; the nail 40 passing thru the sleeve and securing it in fixed position to the wall 41 while the end 29 of the device is employed in the manner described to engage a strand 36a of the wire mesh 36 to hold 75

the latter stretched in furred relationship to the wall 41.

I claim:

1. In a device of the class described, a wire coiled to form a relatively rigid sleeve, thence passing inwardly thru the sleeve and there forming an elongated U-shaped loop.
2. Lath comprising: plaster-impervious sheets, spaced parallel re-enforcing rods behind said sheets, sleeves distributed over the outer surface of said sheet in rows over and corresponding to said rods with the axis of each sleeve normal to the corresponding sheet, wire mesh superimposed over said sheets in spaced relationship with portions of said mesh resting on corresponding of said sleeves; each sleeve further comprising an

integral wire extent passing inwardly thru the sleeve, thence thru the underlying sheet, thence around the underlying portion of the corresponding rod, thence outwardly thru said sheet and thru said sleeve, thence bent sharply over the upper edge of said sleeve and extending parallelly under the mesh to a remote strand, thence bent sharply over the said strand and thence continuing over and above said mesh, and then terminating in an end tied relative to said mesh. 10

3. In a building frame the combination of the lath as in claim 2 and to which frame the rods thereof are welded to form a structural part of the frame while retaining the lath contiguous to the face of the frame. 15

ARTHUR M. McLELLAN.
